UNITED STATES PATENT OFFICE.

JOHN S. PALMER, OF PROVIDENCE, RHODE ISLAND.

GEM-SETTING.

SPECIFICATION forming part of Letters Patent No. 236,835, dated January 18, 1881.

Application filed November 10, 1880. (Model.)

To all whom it may concern:

Be it known that I, JOHN S. PALMER, of the city of Providence, in the county of Providence and State of Rhode Island, have invented 5 certain new and useful Improvements in the Method of and Means for Setting Precious or other Stones in Articles of Jewelry; and I do hereby declare that the following is a full, clear, and exact description of the invention, 10 which will enable others skilled in the art to which it appertains to make and use the same, reference being had to the accompanying drawings, and to the letters of reference marked thereon, which form a part of this specification. 15

My invention relates to a novel method and novel means of holding precious and other stones in place while being set, and of affording a fixed and permanent bearing for the same 20 when set; and the nature of the invention will be made plain from the following description.

Figure 1 illustrates the several parts of a finger-ring made in accordance with my invention, the parts being detached and ready 25 to be put together, it being, however, understood that the invention is applicable generally to jewelry and similar articles in which stones or jewels are to be inserted, a ring merely serving by way of illustration. Fig. 2 shows the ring with the several pieces bound 30 temporarily in place, ready for soldering or cementing. Fig. 3 shows a ring with a portion of the stone broken away to exhibit my improvement of its interior construction, consisting, mainly, in one or more springs, which serve 35 as springs at a certain stage of the fabrication, and are subsequently converted into fixed bearings.

— A is the ring proper; B, the bezel or rim; 40 C, the stone, and D the springs which I employ to hold the stone in position in the bezel.

The springs D (one or more, accordingly as 45 circumstances may require) being placed in the bed or cup e of the ring or other article, and supported loosely, as shown, upon their legs, and by the wall or side of the cup, if need be, the stone is next laid upon the spring or springs, and then the bezel is placed to encompass the stone. During these latter steps, as 50 also during the temporary wiring or binding of the parts preparatory to soldering or cement-

ing of the bezel to the collet, the springs perform the duty not only of upholding the stone, but also, by reason of their yielding or springing quality, to permit the most perfect adaptation of the parts without any impediment from the stone, inasmuch as the latter, resting upon these springs, may be pressed down as may be needful, the springs, however, exerting a constant pressure to bear it upward snugly 55 against the bezel.

When the bezel has been fastened by cementing, soldering, or otherwise, the springs are firmly soldered or cemented to the collet, or adjacent parts upon which they may have 60 previously rested by slipping the solder or cement into the opening f of the cup, and they then cease to be springs and become fixed permanent bearings for the stone. When the cup has a closed bottom the solder or cement 70 should be placed within it at the same time that the springs are put in.

The number of springs used may vary at option, depending also, in some measure, upon the size, shape, and character of the article of 75 jewelry to be manufactured.

Besides the advantages above named due to this method of manufacture, and to the springs in the double capacity of a yielding support during the manufacture and of a fixed bearing 80 support in the completed article, the advantages over the ordinary methods of cutting and burnishing the stones into the settings are a saving of labor and a much neater finish, as the stone is set at the same time and by 85 the very act of soldering on the top or bezel. —

I claim—

1. In the setting of stones in jewelry, the described method of holding the stone in place by means of a spring or springs while being 90 set, and of affording a fixed bearing for the same when set by securing such spring or springs in a fixed position.

2. In a gem-setting, one or more springs, D, applied and secured to hold the stone in position, substantially as and for the purpose specified. 95

JOHN S. PALMER.
